ELECTRICAL CONNECTING DEVICE

Henry Cecil Acuff, Knoxville, Tenn.

Application January 6, 1937, Serial No. 119,177

3 Claims. (Cl. 247—3)

This invention relates to electrical connecting devices, and has particular reference to devices of this general type adapted to be continuously disposed along the wall so as to afford an outlet 5 at any desired point.

One object of the invention is to provide a device of the character described which is particularly simple and inexpensive in construction, and which is durable, reliable and efficient in use.

10 Another object of the invention is to furnish a device of the type mentioned wherein the casting structure consists of yieldably related parts to cause a snug contact electrically with a plain bus bar.

15 Another object of the invention is the provision of a device of the nature set forth which is especially simple to assemble and install, and which may be rolled in coils, if desired, for inexpensive shipment.

20 Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

30 In the drawing:

Figure 1 is an isometric view, partly in section, showing a device embodying the invention.

Fig. 2 is a sectional view showing the device in 35 course of being assembled.

Fig. 3 is an isometric view, partly in section, showing a modified form of the invention.

Fig. 4 is a similar view of a detail of the invention.

40 Fig. 5 is a view of the device in coil form.

The advantages of the invention as here outlined are best realized when all of its features and instrumentalities are combined in one and the same structure, but, useful devices may be produced embodying less than the whole.

45 It will be obvious to those skilled in the art to which the invention appertains, that the same may be incorporated in several different constructions. The accompanying drawing, therefore, is submitted merely as showing the preferred exemplification of the invention.

50 Referring in detail to the drawing, 10 denotes a device embodying the invention. The same may include an elongated insulating means, such as a 55 one piece member 11, having longitudinal side

portions 12, and a center portion 13 therebetween, said portions being spaced from each other to provide the longitudinal parallel passages 14. The side and center portions are flexibly related to each other to permit expansibility of the passages 14 for a purpose hereinafter described. This is best realized by making the means 11 of a flexible composition material, especially if a one piece construction thereof is used. 5

The passages or slots 14 are continuously open 10 at one face of the member 11, but are closed as shown near the bottom of the member. Disposed longitudinally within these slots are bus bars or conductor elements 15 so related to a wall of each slot as to permit the contact prongs of a conventional electrical connector or cap fitting to be inserted in the slots and between a wall of each slot and a conductor element 15 in wiping or frictional contact with the latter. This may be effected by a suitably spaced relation as between an element 15 and a wall such as 16; or by a beveled or rounded cross section of the conductor element; and of course the flexibility of the member 11 is likewise an aid. Without limiting the invention, and by way of illustrating a preferred embodiment thereof, the slots 14 may be longitudinally enlarged along a line spaced from the mouths of the slots at the face 17, for example, by means of grooves 18. The elements 15, which may be standard conductor wires are larger in diameter 20 than the width of the slots 14, but less than the width at the enlargements 18, the wires being partially received in the latter as shown. 25

The method of making the device 10 will now be briefly described. The member 11 may be 30 molded as a one piece construction, complete as shown. Then the wires 15 are pressed into the slots, causing expansion thereof as shown in Fig. 2, until the wires snap into the grooves 18. The device 10 is now completely assembled. 35

To install the device 10, the same is positioned along the wall of a room in any desired position or elevation, and may be secured to the wall by screws through holes 19. The wires 15 are suitably connected into the house circuit at any desired point. Blocks 20 may be placed at the ends of the member 11 to close the same as shown, and these blocks may be secured to the wall by screws through the holes 21. 40

In shipment, the device 10 may be rolled into 45 the form of a coil as shown at 22 for compactness, this being an important advantage.

In principle, the flexible relation between the side and center portions 12, 13 of the member 11 is important, since it not only facilitates the as- 50

sembling, but acts to retain the conductor elements 15 without requiring other securement means, and, further, affords the resilience in the contacting engagement of the prongs with the 5 elements 15. Hence no spring contacts need be used, plain straight wires 15 being thus available, and the means 11 serving as the yielding agent as well.

Should it be desired to hold the conductor 10 wires 15 quite rigidly, clips or U-shaped elements 23 may be employed transversely of the member such as 11a with their arms 24 inserted into the slots 14a. These clips may be disposed several feet or more apart from each other. They consist of insulating material, such as Bakelite, and their arms may be grooved as at 25 to engage or interlock with the wires 15. The central portion 13a of the member 11a may be undercut as at 26 to receive the upper part of the clip. 20 A perforation at 27 will align with a hole 19 to permit a screw to hold both the clip and the member 11 as a unit. In all other respects the modification of Fig. 3 is like the construction of the device 10.

25 It will be understood that the device 10 may be made in various sizes and shapes. The material for the member 11 may consist of rubber like or other material, that is semi-soft or possibly a little harder. The bus bars or elements 15 may 30 consist of hard drawn copper wires; the term bus bar and conductor wire being used as equivalents herein. The device 10 may be used with any standard pronged connector fitting, the slots 14 being deep enough to receive the same, and 35 the spacing between the walls or surfaces 16 and the bus bars 15 being such as to cause a slight resilient expansion of the slots 14 upon inserting the said prongs, to thus effect a good electrical contact. When the prongs enter, they strike the 40 bus bars to one side of center, and with a cam action due to the roundness of the bus bars, move into sliding contact therewith. This action may be aided by the tapered and frequently somewhat sharpened ends of the conventional 45 prongs.

In practice, in order to install the device 10, it is preferred first to cut the member 11 and the elements 15 to the required length. Then a slot 14 is opened at one end by a suitable tool, and an end of the element 15 inserted and thus 50 continuously pressed downward into the slot until it lies in its groove. This operation can be performed, if desired, after the member 11 has been secured to the wall. Or the elements 15 may be fed endwise into the slots and grooves 55 by a simple sliding action. The holes 19 need

not be preformed, since holes can be drilled in the member 11 wherever desired.

It will thus be seen that I have provided a device which fulfills the objects of the invention and is well adapted for practical use. 5

I claim:

1. An electrical connector device including a one piece elongated member consisting of a flexible composition insulating material, said member having spaced longitudinal slots for receiving at any point therealong the contact prongs of an electrical connector, and electrical conductor wires in said slots disposed to contact said prongs, each of the slots having a lateral groove therein for partially receiving its conductor wire, 15 and a U-shaped element of insulating material having its arms inserted into the slots to press the conductor wires inward of their grooves. 10

2. An electrical connector device including an elongated means having spaced longitudinal slots for receiving at different points therealong the contact prongs of an electrical connector, electrical conductor wires in said slots disposed to contact said prongs, each slot having a lateral groove for partially receiving its conductor wire, 20 said means comprising a central longitudinal portion intermediate of the slots and longitudinal side portions at the outside of the slots, said portions having coaction with each other, to 25 yieldingly resist widening of the slots, and insulator means snugly inserted in the slots in close fitting engagement with the conductor wires and serving to press them into said grooves, 30 said slots being otherwise open to receive said contact prongs. 35

3. An electrical connector device including an elongated means having spaced longitudinal slots for receiving at different points therealong the contact prongs of an electrical connector, electrical conductor wires in said slots disposed to 40 contact said prongs, each slot having a lateral groove for partially receiving its conductor wire, said means comprising a central longitudinal portion intermediate of the slots and longitudinal side portions at the outside of the slots, 45 said portions having coaction with each other to yieldingly resist widening of the slots, and insulator means having sections inserted in said slots, said sections having grooves opposed to the 50 grooves of the respective slots and serving to engage the conductor wires, the insulator means retaining the conductor wires in the grooves of the slots to permit said contact prongs to be inserted into the grooves alongside of the conductor wires and in contact therewith. 55

HENRY CECIL ACUFF.
